US00D518272S

(12) United States Design Patent (10) Patent No.: US D518,272 S
(45) Date of Patent: * Apr. 4, 2006

(54) BAKED SNACK CHIP HAVING SCALLOPED EDGES

4,752,493 A 6/1988 Moriki
4,844,919 A 7/1989 Szwerc
4,889,733 A 12/1989 Willard et al.

(75) Inventors: Jessica H. Schwartzberg, Maplewood, NJ (US); Mihaelos N. Mihalos, Palisades Park, NJ (US); Theodore Janulis, Randolph, NJ (US); Barbara E. Baumann, Bedminster, NJ (US)

(73) Assignee: Kraft Foods Holdings, Inc., Northfield, IL (US)

FOREIGN PATENT DOCUMENTS

JP 55018250 8/1980

() Term: 14 Years

OTHER PUBLICATIONS

(21) Appl. No.: 29/230,244

U.S. Appl. No. 29/217,431, filed Nov. 17, 2004, Ferguson et al.

(22) Filed: May 19, 2005

U.S. Appl. No. 11/101,701, filed Apr. 8, 2005, Mihalos et al.

Related U.S. Application Data

U.S. Appl. No. 29/227,291, filed Apr. 8, 2005, Mihalos et al.

U.S. Appl. No. 29/229,045, filed May 3, 2005, Ferguson et al.
